[57] CLAIM

The ornamental design for the carpet dyeing machine, as shown and described.

DESCRIPTION

FIG. 1 is a perspective view of the carpet dyeing machine constructed in accordance with the present invention and illustrating my new design;

FIG. 2 is a top plan view of the carpet dyeing machine of FIG. 1;

FIG. 3 is a bottom plan view of the carpet dyeing machine of FIG. 1;

FIG. 4 is a side elevational view of the carpet dyeing machine of FIG. 1, taken from the left side thereof;

FIG. 5 is a front elevational view of the carpet dyeing machine of FIG. 1;

FIG. 6 is a side elevational view of the carpet dyeing machine of FIG. 1 taken from the right side thereof; and

FIG. 7 is a rear elevational view of the carpet dyeing machine of FIG. 1.

FIG. 1

FIG. 2

FIG. 3

FIG. 4

FIG. 5

FIG. 6

FIG. 7
